US00D943734S

(12) **United States Design Patent** (10) **Patent No.:** **US D943,734 S**
(45) **Date of Patent:** **** Feb. 15, 2022**

(54) **MASK**

(71) Applicant: **Dongguan Liangcail Silicone Electronics Technology Co., LTD,**
Dongguan (CN)

(72) Inventor: **Guang Fan**, Dongguan (CN)

(**) Term: **15 Years**

(21) Appl. No.: **29/730,326**

(22) Filed: **Apr. 3, 2020**

(51) **LOC (13) Cl.** **29-02**

(52) **U.S. Cl.**

USPC **D24/110.1**

(58) **Field of Classification Search**

USPC D24/110, 110.1–110.4, 162; D29/102,
D29/105–108, 110

CPC . A41D 13/11; A41D 13/1107; A41D 13/1115;

CLAIM

The ornamental design for a mask, as shown and described.

DESCRIPTION

FIG. 1 is a front elevation view of a mask showing my new design;

FIG. 2 is a back elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front perspective view thereof; and,

FIG. 8 is a rear perspective view thereof.

1 Claim, 5 Drawing Sheets
